UNITED STATES PATENT OFFICE.

CAROLINE L. PIERCE, OF MIAMI, FLORIDA.

WATERPROOF LABEL HOLDER.

Application filed April 19, 1923. Serial No. 633,167.

To all whom it may concern:

Be it known that I, CAROLINE L. PIERCE, a citizen of the United States, residing at Miami, in the county of Dade and State 5 of Florida, have invented certain new and useful Improvements in Waterproof Label Holders, of which the following is a specification.

This invention relates to holders, designed 10 primarily for retaining a card, tag or plate having indicia to set forth the name or other data of a tree, shrub or plant to which the holder is attached, but it is to be understood that a holder, in accordance with this 15 invention can be employed for retaining a card, tag or plate provided with indicia of a character other than that as referred to, and the invention has for its object to provide, in a manner as hereinafter set forth, a holder including means for not only 20 permanently connecting a name card, tag or plate therewith, but further for protecting the same from dust, dirt, moisture or accidental removal, whereby the card, tag 25 or plate is maintained in good condition for an indefinite period, so that one can clearly, after many years, read the indicia or data on the card, tag or plate as applied to the object to which the holder is attached. 30 Further objects of the invention are to provide a holder for the purpose set forth, which is simple in its construction and arrangement, strong, durable, water proof, efficient in its use, readily attached in position 35 for the purpose of indicating an object, and inexpensive to manufacture.

With the foregoing and other objects in view, the invention consists of the novel construction, combination and arrangement 40 of parts as hereinafter more specifically described and illustrated in the accompanying drawings, wherein is shown an embodiment of the invention, but it is to be understood that changes, variations and modifications 45 can be resorted to which come within the scope of the claim hereunto appended.

In the drawings wherein like reference characters denote corresponding parts throughout the several views:—

50 Figure 1 is a front elevation of a holder, in accordance with this invention.

Figure 2 is a section on line 2—2, Figure 1.

Figure 3 is an elevation of the body portion of the holder prior to the securing of 55 the card, tag or plate therewith.

Figure 4 is an elevation of the trans-

parent protective panel for that face of the card, tag or print provided with indicia.

Figure 5 is an elevation of the card, tag or plate, which is connected with the holder. 60

The holder is constructed of metallic material, of any suitable thickness, and comprises a body portion 1, having beveled corners 2, and longitudinally scored as at 3, 4, and further transversely scored, as at 5, whereby the marginal portions 6, 7 and 8, can be bent over to oppose the forward face of the body portion 1 to provide retaining flanges 9, 10 and 11. Formed integral with the body portion 1, is a breast portion 12, of tapering contour, and which is scored as at 13, 14, to provide for the convenient bending of the marginal portions 15, 16 to oppose the forward face of the breast portion 12, thereby providing inclined retaining flanges 17, 18. 65

Formed integral with the breast portion 12, is a neck portion 19, having beveled corners 20 and 21. The neck portion 19 is longitudinally scored as at 22, 23, and transversely scored as at 24, to provide for the convenient bending of the marginal portions 25, 26 and 27, against the outer face of the neck portion 19, thereby providing retaining flanges 28, 29 and 30. The neck 70 portion 30 is formed with an opening 31. 75

The marginal portions 15 and 16 of the breast portion 12, have their lower ends spaced from the upper ends of the marginal portions 6, 7 of the body portion 1. The 80 lower ends of the marginal portions 15, 16, are inclined and the upper ends of the marginal portions 6, 7 are also inclined, but the inclination of the lower end of the marginal portions 15, 16, extends in an opposite direction with respect to the inclination at the upper end of the marginal portions 6, 7, whereby when the flanges 9, 11, 17 and 18 are formed, the upper ends of the flanges 9 and 11 will be brought into abutting engagement with the lower ends of the flanges 17 and 18. 85

The upper ends of the marginal portions 25 and 27 are inclined and the ends of the marginal portion 26 are inclined and by this arrangement when the flanges 28, 29 and 30 are set up, the upper ends of the flanges 28 and 29 will abut against the ends of the flange 30. The lower ends of the flanges 28, 29 are spaced from the upper 90 ends of the flanges 17 and 18. 100

Mounted within the holder is a protec-

tive member 32, of transparent material, preferably mica or celluloid, and the member 32 conforms in contour to the shape of the holder after the flanges have been formed, and the said member 32 is of the same length and width as the holder.

includes a body portion, a breast portion and a neck, of the same contour as the body portion, breast portion and neck of the holder.

The card, tag or plate is indicated at 33, and which may be of any suitable material, and which conforms in contour to the shape 10 of the member 32, as well as being of a length and width equal to the length and width of the member 32. The member 32 is provided with an opening 34, and the member 33 with an opening 35. The openings 34, 35, register with each other and also 15 register with the opening 31 at the back of the holder.

Although two forms are shown for connecting a hanger or wire with the holder, yet it is to be understood that any suitable means or arrangement can be employed for such purpose. 55

The holder is secured in position by any suitable means extending through the registering openings 31, 34 and 35.

Although the preferred embodiment of the holder, in accordance with this invention, is as illustrated and described, yet it is to be understood that changes in the details of construction can be had which will fall within the light of the invention as claimed. 65 66

What I claim is:—

When setting up the holder for the purpose of permanently connecting the member 33 therewith, the member 33 is positioned against the forward face of the holder prior 25 to the forming of the flanges. After the member 33 has been positioned against the holder, and arranged to align with the several scores thereof, the protective member 32 is positioned against the face of the member 33 which is provided with the desired indicia, and with the member 32 flush with the edges of the member 33. After 30 the members 32 and 33 have been mounted with respect to the body portion, the several marginal portions are bent to provide the flanges whereby the members 32, 33 are 35 permanently connected to the holder.

The flanges overlap the member 33, thereby providing, in connection with the member 32, means to protect the member 33 from dust, dirt or moisture, or further to prevent the tampering with said member 33.

The flanges when formed are bent into snug contact with the member 32.

45 The member 32, as well as the member 33

What I claim is:—
A holder for the purpose set forth comprising a rectangular body portion having its lower end formed with an inturned flange and each of its sides provided with an inturned flange, a tapering breast portion integral with the top of said body portion and having each side thereof provided with an inturned flange, a rectangular neck portion integral with said breast portion and having each of its sides and its free end provided with an inturned flange, an indicia carrying means positioned against the forward face of said body, breast and neck portions and having its edges inclosed by said flanges, a transparent protecting member positioned against said indicia carrying means and having its edges inclosed by said flanges and further having its outer face overlapped and engaged by said flanges, said member and means conforming in contour to the shape of said body, breast and neck portions, said neck portion provided with an opening, and said means and member having registering openings aligning with the opening in said neck portion.

In testimony whereof, I affix my signature hereto.
